UNITED STATES PATENT OFFICE.

JAMES J. CONWAY, OF BELLINGHAM, WASHINGTON.

COOKING UTENSIL.

No. 895,433.

Specification of Letters Patent. Patented Aug. 11, 1908.

Application filed June 25, 1907. Serial No. 380,780.

To all whom it may concern:

Be it known that I, JAMES J. CONWAY, of Bellingham, in the county of Whatcom, State of Washington, have invented certain 5 new and useful Improvements in Cooking Utensils, of which the following is a specification.

The object of my invention is to produce a cooking utensil or broiler, as it may be designated by reason of its being especially adapted for cooking meats, whereby the grease and juices of meat are not only rendered available for basting purposes, but removed away from the direct heat of the 10 fire and thereby prevented, in large measure, from burning and throwing off smoke and noxious odors.

In the accompanying drawing, which constitutes a part of this application, Figure I is 15 a perspective view of my broiler in its preferred form of embodiment, Fig. II is a vertical section of the same from front to rear, Fig. III is a view similar to Fig. II, showing a slight modification of the broiler, and Fig. 20 Fig. IV is a side elevation of the broiler shown in Fig. I and indicating additional modification.

Referring to the numerals on the drawing, 1 indicates the bottom plate of my broiler, which consists of a plate of steel or iron of 25 any suitable dimensions. The bottom-plate 1 is preferably a flat plate which may lie in close juxtaposition with the top plate of a stove, or which may be in like manner set upon the bottom or a shelf of an oven. It is 30 provided on three sides with walls 2, 3, and 4, the wall 3 being at the rear end of the utensil. There is no wall in front, but instead thereof a depending trough, preferably composed of opposite side-pieces 5 and 6, a 35 bottom 7 extending the full width of the utensil, and end-pieces 8 and 9, is provided. The upper edges of both of the side pieces 5 and 6 are located below the level of the bottom of the broiler, thereby defining a trough, 40 which, depending, as specified, below the broiler, may overhang the edge of a shelf upon which it is placed, and present the trough for service below the shelf and outside of the edge thereof. The end-pieces 8 and 9 45 are preferably downwardly deflected elongations of the sides 4 and 2, respectively.

The members above described are preferably integrally united into a single casting, the plate 1 being finished in any preferred 50 and usual manner, either with corrugations extending from front to rear, or with a flat

surface upon which, if desired, cakes may be baked.

In practice, the plate 1, as shown on Figs. I and II, is set flat upon the shelf of an oven or any horizontal portion above the fire in any kind of a stove, whether operated by oil, gas, coal or wood, the trough overhanging the front edge of the shelf or portion of the stove upon which the bottom plate 1 of the broiler rests. Owing to the absence of any wall between the bottom plate 1 and the depending trough, any liquid that is deposited upon the upper surface of the plate readily runs off into the trough, and in so doing is not only removed from exposure to direct heat from the fire under the plate 1, but is presented in convenient position, and in available quantity, for basting purposes.

If the construction of the stove does not admit of the placing of the plate 1 upon an oven shelf, or if, in other words, there is no accommodation between the edge of the oven shelf and the oven door for the trough, my broiler may be provided, as shown in Fig. III, with a leg 10 of a height preferably a little greater than the trough by which the whole broiler may be set upon the shelf, indicated by the horizontal line, upon which the broiler rests, as shown in Fig. III.

An important function of the trough being to separate the liquid grease that is exuded from meats in the process of cooking, it may be provided with a pipe 11, as shown in Fig. IV, for drawing off that product, after or irrespective of the basting operation, as desired.

By the use of my invention, the cooking of meats is facilitated and improved. At the same time, a saving of considerable pecuniary value may be effected in grease and fats, or drippings from meats, which ordinarily are consumed by the fire or otherwise wasted.

What I claim is:

1. In an article of the kind described, the combination with a bottom plate, rear and side walls, of a trough depending below the surface of the bottom plate unobstructed on the front side thereof, and comprising, with end and bottom pieces, side pieces both located below the level of the bottom of the broiler.

2. In an article of the kind described, the combination with a bottom-plate, rear and side walls, of a trough depending below the surface of the bottom-plate on the unobstructed front side thereof, and provided

with side and bottom pieces, the upper edges of both the side-pieces of the trough being located below the upper surface of the bottom-plate, and with end-pieces constituting deflected elongations of the side walls aforesaid.

3. In an article of the kind described, the combination with a flat bottom-plate adapted to lie in close juxtaposition with the top plate or the like member of a stove, and rear and side walls extending upwardly from the bottom plate, of a depending trough, longitudinally co-extensive with the bottom plate, communicating therewith at its unobstructed front edge, and adapted to overhang the edge of the stove member when the bottom-plate is laid thereon, the upper edges of both

the side pieces of the trough being located below the upper surface of the bottom-plate.

4. In an article of the kind described, the combination with an unobstructed flat bottom-plate, provided upon three sides with walls, and adapted to lie upon the top-plate or like member of a stove in close juxtaposition therewith, of a trough depending below the upper surface of the bottom-plate and operatively communicating therewith.

In testimony whereof I have hereunto signed my name in the presence of two subscribing witnesses.

JAMES J. CONWAY.
